UNITED STATES PATENT OFFICE.

LEWIS P. WENTZELL, OF GREENSBURG, PENNSYLVANIA.

LOCK.

1,295,400.

Specification of Letters Patent. Patented Feb. 25, 1919.

Application filed September 11, 1918. Serial No. 253,582.

To all whom it may concern:

Be it known that I, LEWIS P. WENTZELL, a citizen of the United States, residing at Greensburg, in the county of Westmoreland and State of Pennsylvania, have invented new and useful Improvements in Locks, of which the following is a specification.

This invention relates to a lock and more particularly to an improved form of lock for locking a lever in a plurality of positions and has for its primary object to provide a lock that will effectively lock a switch throwing lever in either of its two positions without the necessity of more than one lock of an inexpensive construction.

An object of the invention is to provide a lock of simple construction the casing of which being constructed to take the place of the weight usually associated with a switch throwing lever.

Besides the above my invention is distinguished in a construction of a lock in which the essential elements are fully protected against distortion.

With these and other objects in view the invention will be better understood from the following detailed description taken in connection with the accompanying drawing wherein:

Figure 1 is a cross sectional view of the lock.

Fig. 2 is a longitudinal sectional view.

Fig. 3 is an end elevation.

Fig. 4 is a diagrammatic view showing the invention in use upon a switch throwing lever.

At the start I wish to call attention to the fact that although I have described and shown my invention coöperating with a switch throwing lever the same may be used in a plurality of other manners than illustrated.

That form of my invention illustrated in the drawing consists of a casing 1 weighted for facilitating the throwing of the lever 2. This casing 1 is rotatably mounted on the lever 2 as shown at 3 so that the casing may be rotated upon the lever in the throwing of the latter. The under surface of the

casing 1 is recessed as indicated at 4 so as to receive the locking mechanism 5. This locking mechanism consists of a pawl swingingly mounted on a pin 7 and is provided with a cam shaped extremity 8 and adapted to engage the stationary catch 9. In the particular showing there are two of these catches 9 arranged at the two positions that the lever 2 is to assume. The hook shaped extremity 8 is provided with a cam face 10 to facilitate engagement of the pawl 6 with the catch 9. The remaining extremity 11 of the pawl which is of a curved formation is arranged to be engaged by an arm 12 for retracting the pawl out of engagement with the catch 9. This arm 12 is fixed on a shaft 13 journaled in the casing 11 with one end thereto arranged opposite an opening 14 in the casing and provided with a key receiving recess 15 which may be of any configuration. To complete the invention I provide a handle 16 for turning the casing 1 upon the lever 2.

From the foregoing description taken in connection with the accompanying drawing it should be apparent that upon gripping the handle 16 the lever 2 may be thrown from its full line position, Fig. 4, to its dotted line position and at the same time the casing 1 may be rotated on the lever 2 so that the recess 4 may be brought into registration with a catch 9 for allowing engagement between the catch and pawl. It is of course to be understood that the invention may be constructed in various other manners than shown and the parts may be associated in different manners and therefore I do not desire to be limited in any manner except as set forth in the claims hereunto appended.

Having described my invention, what I claim is:

1. In combination with a pivoted lever adapted to assume two positions, a stationary catch arranged at each position of the lever, a lock casing rotatably mounted on the lever, a pivoted pawl within the casing adapted to engage either of said catches, a handle upon the casing and a key operated

arm for moving the pawl to inoperative position.

2. In combination with a pivoted lever adapted to swing to two horizontal positions, a stationary catch arranged at each position of the lever, a lock casing rotatably mounted on the lever and having its under

surface recessed, a pivoted pawl arranged in the recess of the case and adapted to engage either of said catches and a handle 10 for rotating the casing on the lever and for moving the latter.

In testimony whereof I affix my signature.

LEWIS P. WENTZELL.
